CLAIM

The ornamental design for a putting mirror, as shown and described.

DESCRIPTION

FIG. 1 is a top perspective view of a first embodiment of a putting mirror according to our new and ornamental design; FIG. 2 is a top plan view thereof;

FIG. 3 is a bottom plan view thereof;

FIG. 4 is a front elevation view thereof;

FIG. 5 is a rear elevation view thereof;

FIG. 6 is a left elevation view thereof;

FIG. 7 is a right elevation view thereof;

FIG. 8 is a top perspective view of a second embodiment of a putting mirror according to our new and ornamental design;

FIG. 9 is a bottom perspective view of the second embodiment of the putting mirror;

FIG. 10 is a top plan view of the second embodiment of the putting mirror;

FIG. 11 is a bottom plan view of the second embodiment of the putting mirror;

FIG. 12 is a front elevation view of the second embodiment of the putting mirror;

FIG. 13 is a rear elevation view of the second embodiment of the putting mirror;

FIG. 14 is a left elevation view of the second embodiment of the putting mirror; and,

FIG. 15 is a right elevation view of the second embodiment of the putting mirror.

The broken lines illustrate portions of the putting mirror that form no part of the claimed design.
